UNITED STATES PATENT OFFICE.

GEORGE J. WILKMAN, OF CHICAGO, ILLINOIS, ASSIGNOR TO IDEAL SHEET METAL WORKS, A CORPORATION OF ILLINOIS.

RADIATOR.

1,356,897.

Specification of Letters Patent. Patented Oct. 26, 1920.

Application filed November 10, 1918. Serial No. 130,504.

To all whom it may concern:

Be it known that I, GEORGE J. WILKMAN, a citizen of the United States, residing in Chicago, in the county of Cook and State 5 of Illinois, have invented certain Improvements in Radiators; and I do hereby declare that the following is a full, clear, and exact description thereof, reference being had to the accompanying drawings, and to the 10 characters of reference marked thereon, which form a part of this specification.

This invention relates to improvements in radiators in which heat is interchanged from a medium of one temperature flowing 15 in definite passages in the radiator to a medium of another temperature flowing in other definite passages therein and separated from the first named passages by thin walls. The invention is herein shown as embodied 20 in an automobile radiator through which the cooling water of the engine is passed to bring it into heat interchange relation with air passed through the radiator.

The invention relates more specifically to 25 a novel construction of so called honey-comb core for such radiators and the purpose of the invention is to simplify the core construction; to provide a maximum area of air and water passages in a radiator of given 30 dimensions; to reduce the weight and the cost of the radiator as compared to its cooling efficiency; to reduce to a minimum the area of double thickness walls between the air and water passages; to provide a construction which is simple to manufacture 35 and which does not place unusual or objectionable bending or tensile strains on the metal in forming the core elements; to reliably brace the core construction throughout 40 its length by means which do not restrict the area of air and water passages and to thereby produce a rigid and sturdy radiator core and to otherwise simplify and improve radiator constructions.

45 The invention consists in the arrangements and combination of the parts shown in the drawings and described in the specification and the invention is pointed out in the appended claims.

50 In the drawings:

Figure 1 is a side view of one of the elements from which the radiator core is made.

Fig. 2 is an end elevation of a fragment of radiator embodying my invention.

Fig. 3 is a vertical section on the line 3—3 55 of Fig. 4.

Fig. 4 is a cross section on the line 4—4 of Fig. 3.

Fig. 5 is a broken perspective view of a fragment of the radiator core. 60

The radiator core is composed of a plurality of like elements, each consisting of two sheet metal corrugated walls or units so associated as to form between them air passages, and so assembled relatively to each 65 other as to form between the separate elements defined water passages which are separated from the air passages by the thin sheet metal walls of the elements.

Each element of the radiator may be made 70 of two corrugated sheet metal plates of a material possessing good heat conductivity, as brass or copper, suitably joined at their upper and lower edges to complete the element and to form air passages therein, or each 75 element may be made of a single corrugated sheet metal plate 10 (Fig. 1) which is folded upon itself to produce the full element with the free edges thereof joined together in any suitable manner. 80

When the element is made of a single sheet of metal folded upon itself and joined at its free edges in the manner suggested, a plain strip of sheet metal of a width substantially equal to the thickness of the radiator body from front to rear, and therefore equal to the length of the air passages through the radiator, is passed through a corrugating machine or is formed by corrugating dies so as to produce alternate elevated and depressed sections 12, 11, respectively, joined by oblique sections 14 to avoid sharp bends between the elevated and depressed sections and also to avoid sharp corners to trap sediment contained in the cooling water. The said elevated sections 12 at the margins of the sheet 10 are off set outwardly at 15 beyond the plane of the outer faces of said sections, the off set portions being joined to the planes of the elevated sections by oblique or inclined portions 16 constituting continuations of the oblique portions 14 joining the elevated and depressed sections. The said depressed sections 11, the 95 100

end margins 11^a of which are not offset relatively to the planes of said depressed sections, are formed to provide along their lengths a plurality of hollow protuberances 17 which 5 extend inwardly from the inner faces of said sections, each of said sections being herein shown as provided with three of such protuberances, one at each end and the other at the longitudinal center thereof. The said 10 protuberances may be formed in the corrugating operation or may be formed in a separate operation.

After the plates have been formed in the manner described, and as shown in Fig. 1, 15 they are folded upon themselves to produce the elements A, B, of the core and their free ends are locked together by any suitable form of interlocking seam 18, or otherwise joined to produce air tight joints. The elements A, B are identical in structure but are 20 edgewise reversed when assembled in the core so that the elements B are raised above the elements A to bring the horizontal air passages 20, which are formed between the 25 elevated sections 12, laterally out of line or staggered with respect to each other in the assembled core, as shown in Figs. 2 and 3.

In the construction shown the elements B are arranged with their interlocked edges 30 18 at the top of the core while the interlocked edges of the elements A are at the bottom of the core. When the sheets are folded to form the elements A, B, the protuberances 17 at the ends and at the centers 35 of the members meet in abutting relation to form between the air passages 20 vertical connecting passages 21. The said vertical passages 21 are normally filled with moving air which adds additional surface against 40 which the air impinges at one side of each wall and also adds additional cooling surface for the water in the water passage at the other side of said wall.

The said elements are assembled with the 45 elevated plane sections 12 of each element opposite to the depressed plane sections 11 of adjacent elements, as best shown in Figs. 3 and 5, thus disposing adjacent horizontal rows of air passages 20 out of line with each 50 other. The off set and margins 15 of the elevated sections 12 at the edges of the elements fit flat against the plain end margins 11^a of the depressed sections at the corresponding edges of the elements, when the 55 elements are so assembled, to close the spaces between said elements at the ends of the core, as best shown in Figs. 4 and 5, and said off set end margins 15 serve to space the elements apart between the front and rear 60 edges of the elements to form generally upright, tortuous water passages 22 between the adjacent elements. The arrows in Fig. 3 indicate the courses of the water passages between the elements. The water passages

of the core are open at the upper side of the 65 core to the water space of the radiator above the same and are open at the lower side of the core to the water space of the radiator below the core. After the elements have been assembled, with their margins 15 and 70 11^a and the protuberances 17 in contact, the core is dipped in solder to the depth of the offset portions 15 and the end abutting protuberance 17, whereby the sheets are firmly secured together and the water passages are 75 thereby sealed at the front and rear faces of the core.

By reason of the construction described wherein the offset margins 15 of the portions 12 are brought flatwise in contact with the 80 end margins 11^a of the portions 11 of the wall elements, and of the fact that the flat-ended protuberances are likewise brought flatwise in contact with each other, it becomes practicable to solder the parts together with a minimum amount of soldering material, the only solder required being the thin films which are present between the flat contacting faces of the parts. Hence weight, 85 due to solder, is reduced to a minimum. 90

It will be furthermore observed, by reference to Figs. 4 and 5 of the drawing, that the water passages 22 which are formed between the assembled elements, are produced by simple offsets 15 of the elevated portions 12; 95 it being practicable to offset the ends of said portions 12 to produce ample water passages without imposing sharp bending stresses on the offset portions. It will be furthermore observed by reference to said Figs. 4 and 5 100 that the vertical air passages or spaces 21 between the horizontal passages 20 may also be made of ample size without imposing objectionable stress on the metal; said passages or spaces 21 being due to the abutment 105 of the protuberances 17 between the portions 11 which define or bound said passages 21. In this connection it will also be observed by reference to said Figs. 4 and 5, and also to Fig. 2, that the said passages 21 continue to 110 the front and rear sides of the radiator, thus increasing the facility with which air may pass into said flues or passages from the front thereof, both directly rearwardly and upwardly and downwardly from points of 115 ingress of air.

It will, moreover, be observed that the spacing protuberances 17 for the air passages 21 (which also serve to measurably modify the width of the main air passages 120 20) are independent in their spacing functions of the spacing offsets 15 to produce the water channels or passages 22, so that thereby the capacities of the air and water passages may be proportioned to suit different requirements without restriction of other sets of passages. Furthermore, the construction is such that a predetermined ample 125

water capacity may be provided in a given width of core and ample air passages are attainable for efficient radiation.

The mounting of the core in the radiator frame is not herein shown, it being understood that the connection of the core in the frame and the communication of the water passages of the core with the upper and lower water space of the radiator may follow any usual or preferred practice.

An advantage of the construction described, which may be pointed out, is that the provision of the hollow protuberances 17 on the inner faces of the depressed sections 15 of the elements form intercommunicating passages 21 of ample dimensions between and connecting the vertical row of horizontal air passages 20 of each element, while at the same time there is effected, by reason of 20 the abutting contact of said protuberances and the abutting of the off set portions 15 against adjacent elements, rigid co-acting bracing effect between the elements to produce a sturdy core construction. Said protuberances, while having ample dimensions for this abutting bearing engagement, do not materially restrict the intercommunicating air passages 21, said protuberances being made considerably narrower than the sections of the elements on which they are formed.

Another advantage of the protuberances to be noted is that amply dimensioned interconnecting air passages 21 between the main air passages 20 are provided without robbing the capacity of the water spaces between the core elements. In fact the provision of said hollow protuberances, which are in open communication with said water passages, adds to the dimension of the water passages and further adds to the area of the wall surface of the air passages, due to the hollow walls of the protuberances which are exposed to the air in the interconnecting air passages 21.

A further advantage of the construction to be noted is that amply dimensioned water and air passages are provided in a core employing a relatively small amount of metal 50 in its construction, with the result that the weight of the core and the cost of its production are materially reduced.

The construction is simple to manufacture and assemble and the contour of the elements is such that the metal is not subjected to objectionable tensile or bending strains in the corrugating and protuberance forming machines.

An important practical advantage of the 60 construction described is that all of the elements of a core construction are duplicates and can be made by a single die or a single pair of corrugating rollers in a corrugating machine. In fact, a strip of metal of suit-

able width and indefinite length may be run 65 through a corrugating machine having a single set of corrugating rollers, and sections of proper lengths cut from the corrugated strip to form the elements of the radiator. Therefore the machine for forming the elements is a simple machine and also its operation is simple and economical.

It will be understood that the invention is capable of embodiment in structures differing somewhat in detail from that illustrated 75 in the drawings and that said invention is not therefore to be limited to the structural details shown except as to claims wherein said details are specifically enumerated. For instance, there may be employed more 80 or a less number of the protuberances or "buttons" 17 and so far as certain features of the invention are concerned, they may be otherwise formed without sacrificing the spacing functions.

I claim as my invention:

1. A radiator comprising a plurality of pairs of spaced sheet metal walls between which are formed vertical water channels, said walls being corrugated to produce like 90 shaped and dimensioned structures of elevated and depressed formation, with the elevations of each wall in register with the depressions of the other wall, each of said walls being provided with a plurality of 95 exterior protuberances struck from the metal thereof and adapted to abut the protuberances of an adjacent wall of another pair to thereby form vertical air passages between adjacent pairs of walls, said passages being open at the front and rear of the radiator, the elevations and depressions of the walls of one pair being respectively disposed opposite to the elevations and depressions of the walls of another pair to 100 form horizontal air passages therebetween and in communication with said vertical air passages.

2. A radiator core section comprising a series of like shaped and dimensioned elements, each composed of two sheet metal walls which are corrugated to form alternate elevated and depressed sections, with the elevated sections in register to produce horizontal air passages, said elements being assembled with the elevated sections of one element in registry with the depressed sections of an adjacent element, the ends of said elevated sections fitting against the ends of the depressed sections of adjacent elements to space the elements apart to form vertical water passages between said elements, said depressed sections being provided with abutting protuberances which space them to form vertical air passages which 115 communicate with the horizontal air passages.

3. A radiator core construction of that

kind having fluid passages therein transversely disposed and separated by thin conducting walls, comprising a plurality of pairs of sheet metal walls corrugated to 5 form alternate like shaped and dimensioned elevated and depressed sections, with the elevated sections of each pair registered to form main passages, and with the depressed sections of each pair also registered and provided with protuberances which abut to 10 space said depressed sections to form therebetween communicating passages between the main passages, said elements being nested with the elevated sections of each element 15 in registry with the depressed sections of adjacent elements, and with the end marginal portions of one element offset toward and lying against the plain marginal portions of the other element to form between the nested elements fluid passages 20 transverse to said main and communicating passages.

4. A radiator core comprising like shaped and dimensioned hollow elements, the walls 25 of each of which are shaped to provide alternate horizontal main air passages and vertical intercommunicating air passages open at the front and rear of the radiator, with abutting spacing protuberances in 30 said vertical passages, said elements being nested, with the main air passages of each element opposite to the vertical communicating passages of the adjacent elements, and with the end margins of 35 the walls bounding the main air passages

offset toward and lying against and soldered to the ends of the end margins of the walls bounding said intercommunicating air passages.

5. A radiator core comprising sidewise 40 nested, hollow elements, all of the same dimensions and contour, and each composed of two opposed sheet metal walls which are corrugated to form alternate elevated and depressed sections, the elevated sections 45 being registered to form between them through horizontal air passages, and the depressed sections being likewise registered and provided with hollow protuberances struck up therefrom which abut endwise 50 and space the latter sections from end to end thereof to form between said through passages communicating passages that are open at the front and rear of the core, the end margins of said elevated sections being offset toward and lying against the end margins of the depressed sections beyond said 55 protuberances to space adjacent elements to provide therebetween vertical water passages.

In witness whereof I claim the foregoing as my invention, I hereunto append my signature in the presence of two witnesses at Chicago, Illinois, this 2nd day of November, 1916.

GEORGE J. WILKMAN.
